UNITED STATES PATENT OFFICE

BRADFORD T. BORDEN, OF LAKEWOOD, CLEVELAND, OHIO, ASSIGNOR, BY MESNE ASSIGNMENTS, TO THE BORDEN COMPANY, OF WARREN, OHIO, A CORPORATION OF OHIO

WORKHOLDER

Application filed January 30, 1928. Serial No. 250,617.

My invention relates to improvements in work holders generally and more particularly to such as are used in connection with die stocks and the like for holding pipe and rods.

Briefly stated, the invention has for its primary object to provide a work holder whereby the pipe or other work can be quickly and accurately centered with respect to the dies or other tools and rigidly locked in place.

Another object of the invention is the provision of a device of this kind including novel cooperating locking and gripping elements incorporating means for facilitating the adjustment for the different standard sizes of work.

A still further and more specific object of the invention is to furnish a work holder which is characterized by a body portion having a large central hole;—the body having a plurality of circumferentially spaced radial bosses communicating with said hole, the bosses being tapped to receive threaded work-engaging shanks, and rotatably mounted abutments which may be turned to variably cooperate with the rear portions of the shanks whereby the proper setting for different sized pipes or other work may be readily arrived at.

Other objects and advantages reside in the construction, combination, and mode of operation of the various parts,—and will be readily understood and appreciated by those skilled in the art as the description proceeds,—reference being had to the accompanying drawings which illustrate several preferred embodiments of the invention.

In the drawings,

Figure 1 is a top plan view of a work holder incorporating my invention;

Figure 2 is a section on the line 2—2 of Figure 1;

Figure 3 is a view partly in plan and partly in longitudinal section of a further modified form of the invention;

Figure 4 is a group perspective of parts shown in Figure 3 with the head of the screw removed from the shank;

Figure 5 is an enlarged developed sectional view of the head of the screw, and

Figure 6 is an elevation of the device shown in Figure 3.

Referring specifically to the drawings wherein the same reference characters have been used to designate the same parts throughout,—the work holder of Figures 1 and 2 comprises a body 1 having a large central hole 2. Circumferentially spaced radial bosses 3 are formed integral with the body at the margin of hole 2, these bosses being tapped to receive the threaded portions of work-engaging shanks 4.

The outer ends of the shanks 4 are provided with knurled heads 5 to facilitate turning of the same and are also preferably provided with transverse holes 6 to receive a turning pin or lever. Description of one shank assembly will suffice for all.

In the form of the invention shown the unthreaded end of the shank has secured at its outer end an externally knurled annular head 60, the inner end of which is provided with a circumferential series of equally spaced holes 61. Diametrically opposite ones of such holes 61 are of equal predetermined depth as shown diagrammatically in Figure 4 and such pairs are adapted to receive the ends of pins 52 tightly fitted in holes 51 in the opposed face of an annulus 50. The different pairs of holes are of different depth and the bottom surfaces of such pairs thus constitute steps cooperating with the abutment formed by the pins 52 and annulus 50. The internal surface of annulus 50 is unthreaded and is of such a diameter that it can slide over the threaded portion of the shank 4.

It is believed to be obvious that pins 52 may be located in a predetermined pair of diametrically opposite holes 61 in head 60 so that advancement of the shank or shanks 4 in a work-engaging direction will be limited by engagement of the annulus 50 with the end of boss 3, the annulus and pins thus forming a distance piece between the shank head and the face of the boss. Thus, the shanks may be adjusted properly according to the size of work to be operated upon. Inasmuch as the holes 61 in effect determine the "size adjustment" of shanks 4, I provide work size markings 63 as indicated in

Figure 6 opposite one or both of the holes of each diametrically opposite pair.

In the embodiment of the invention herein described there are preferably two of the setting shanks, although there may, of course be more. In addition, I preferably employ at least one clamping shank as at 40 (Fig. 1). This has a pivoted hand lever 41.

In use the shanks 4 are screwed outwardly 10 a sufficient distance to free the pins 52 from the sockets 61; then, if the shank is to be set for a different size, the collar 50 is turned until its pins occupy the desired sockets; then the shank is turned in until the inner 15 face of the collar 50 abuts the boss 3 of the annular frame, and this insures the shank being in proper position for the selected size of pipe. With the two shanks 4 thus positioned, the pipe is clamped by screwing in the 20 shank 40 until there is a firm engagement with the ends of the three shanks.

The described embodiment is simple and inexpensive of manufacture, and has the advantage of being adapted to both standard 25 and odd sized work.

Having thus described my invention, what I claim as new and desire to secure by Letters Patent is:

1. In a work holder, a body, a threaded 30 shank threaded thereinto and having a head at its outer end, an adjustable stop on said shank and having opposed rearwardly extending pins, and said head having a circumferential series of surface recesses to receive 35 said pins, said recesses being of different depths and opposed ones of the same being of the same depth.

2. The combination of a body, a shank 40 movable thereinto, and a variable stopping device comprising two mutually engageable members one of which is an abutment and the other of which is a shoulder on the shank, one of said members having a plurality of laterally positioned steps of different height, 45 one of said members being mounted to turn about an axis to select a different step for engagement, whereby the inward movement of the shank may be variably limited.

3. The combination of a body, a shank 50 threaded thereinto, and a variable stopping device comprising two mutually engageable members one of which is an abutment bearing against the body and the other of which is a head on the shank, one of said members having a plurality of laterally positioned steps of different height, one of said members being mounted to turn about an axis by movement in planes normal to the shank axis to select a different step for engagement.

4. The combination of an annular body, a radial screw threaded therein and having a head, an abutment bearing against the body and mounted to turn about an axis, the head and abutment cooperating and one of them 65 having a series of steps arranged in a cir-

cuit about its axis, whereby by turning the abutment a different step may be selected and a different limit for the screw thus provided.

5. The combination of a body, a screw 70 threaded therein and provided with a head, a rotatable abutment between the head and body and adapted to engage both of them and make a distance piece therebetween, said head and abutment constituting cooperating members one of which is provided with a 75 plurality of steps and the other of which is adapted to engage any of such steps according to the angular position of the abutment.

6. The combination of an annular body 80 having an external boss, a screw threaded through the boss and body and having its axis at right angles to the face of the boss, a rotatable abutment bearing against such face of the boss and having its axis at right angles thereto, a head on the screw, said head and abutment cooperating and one of them being provided with a set of steps any one of which the other may engage according to the angular 85 position of the abutment relative to its axis.

7. The combination of a body, a shank 90 threaded thereinto, and a variable stopping device comprising two mutually engageable members one of which is an abutment rotatably surrounding the shank and the other of which is a shoulder on the shank, one of said members having a plurality of laterally positioned steps of different height, whereby the inward movement of the shank may be variably limited according to the angular 95 position of the surrounding member relative to the shank.

8. The combination of an annular body, a radial screw threaded therein and having a head, a rotatable abutment freely surrounding the screw and bearing against the body, the head and abutment cooperating and one of them having a series of steps which the other may selectively engage, said series extending in a circuit about the axis of the 100 screw.

9. The combination of an annular body having an external boss, a screw threaded through the boss and body and having its axis at right angles to the face of the boss, a rotatable abutment freely surrounding the screw bearing against such face of the boss, a head on the screw, said head and abutment cooperating and one of them being provided with a series of steps any one of which the other may engage according to the angular 115 position of the abutment.

In testimony whereof I affix my signature.

BRADFORD T. BORDEN.
